Des. 182,705
Patented May 6, 1958

182,705

LUGGAGE RACK FOR VEHICLES OR SIMILAR ARTICLE

Kenneth W. Binding, Winchester, Mass., assignor to Mar-
ket Forge Company, Everett, Mass., a corporation of
Massachusetts

Application July 25, 1957, Serial No. 47,073

Term of patent 14 years

(Cl. D14—27)

Fig. 1

Fig. 2

Fig. 3

Fig. 4

Fig. 5

Fig. 6

Fig. 1 is a perspective view of a luggage rack for vehicles or similar article showing my new design, the broken line showing of portions of a vehicle being for purposes of illustration only;

Fig. 2 is a plan view;

Fig. 3 is a front elevational view;

Fig. 4 is a rear elevational view;

Fig. 5 is an enlarged side elevational view; and

Fig. 6 is a similar side elevational view taken on the lines 6-6 of Fig. 2.

I claim:

The ornamental design for a luggage rack for vehicles or similar article, substantially as shown and described.
